CLAIM

The ornamental design for a worklight, as shown and described.

DESCRIPTION

FIG. 1 is a perspective view of a first embodiment of a worklight embodying my design;

FIG. 2 is a front view of the worklight of FIG. 1;

FIG. 3 is a rear view of the worklight of FIG. 1;

FIG. 4 is a first side view of the worklight of FIG. 1;

FIG. 5 is a second side view of the worklight of FIG. 1;

FIG. 6 is a top view of the worklight of FIG. 1;

FIG. 7 is a bottom view of the worklight of FIG. 1;

FIG. 8 is a perspective view of a second embodiment of a worklight embodying my design;

FIG. 9 is a front view of the worklight of FIG. 8;

FIG. 10 is a rear view of the worklight of FIG. 8;

FIG. 11 is a first side view of the worklight of FIG. 8;

FIG. 12 is a second side view of the worklight of FIG. 8;

FIG. 13 is a top view of the worklight of FIG. 8; and,

FIG. 14 is a bottom view of the worklight of FIG. 8.

The broken line showing represents portions of the article not claimed and forms no part of the claimed design.
